United States Patent [19]

Marchica

[11] Patent Number: Des. 324,222

[45] Date of Patent: ** Feb. 25, 1992

[54] SECONDARY CONTAINMENT FUEL PUMP BOX

4,880,156 11/1989 Wallet D34/40

[75] Inventor: Frank C. Marchica, East Meadow, N.Y.

Primary Examiner—A. Hugo Word

Assistant Examiner—R. Seifert

Attorney, Agent, or Firm—Anthony J. Casella; Gerald E. Hespos

[73] Assignee: Environmental Protection Products, Inc., N.J.

[57] CLAIM

[**] Term: 14 Years

The ornamental design of a secondary containment fuel pump box, as shown and described.

[21] Appl. No.: 411,573

DESCRIPTION

[22] Filed: Sep. 22, 1989

FIG. 1 is a perspective view of a secondary containment fuel pump box showing my new design on a reduced scale, the broken line showing of a gasoline pump is for illustrative purposes only and forms no part of the claimed design;

[52] U.S. Cl. D15/9.1

FIG. 2 is a top plan view;

[58] Field of Search D15/1, 5-9.1;
417/522, 388, 559, 310; 239/302, 308, 322;
137/523.17, 543.21; 118/300; 427/422; 60/325;
222/3; D34/40

FIG. 3 is a front elevational view, the opposite side being the same;

FIG. 4 is a right side elevational view;

FIG. 5 is a left side elevational view; and

FIG. 6 is a bottom plan view.
